UNITED STATES PATENT OFFICE.

LEWIS EIKENBERRY, OF PHILADELPHIA, PENNSYLVANIA.

IMPROVEMENT IN GOVERNORS FOR STEAM-ENGINES.

Specification forming part of Letters Patent No. 39,903, dated September 15, 1863; antedated September 26, 1862.

To all whom it may concern:

Be it known that I, LEWIS EIKENBERRY, of Philadelphia, in the county of Philadelphia and State of Pennsylvania, have invented a new and useful Improvement in the Construction of Governors for Steam and Other Engines; and I do hereby declare that the following is a full, clear, and exact description of the same, reference being had to the accompanying drawings, forming part of this specification, in which—

Figure 1 is an end or front view of my improved governor. Fig. 2 is a side view of the same. Fig. 3 is a vertical central section in the line $x x$ of Fig. 2. Figs. 4, 5, 6, 7, 8, and 9 are views showing modifications of construction and application of my invention. Figs. 10, 11, 12, and 13 are also modifications.

Similar letters of reference in each of the several figures indicate corresponding parts.

The nature of my invention consists, first, in arranging the arms and levers of a governor in such relation to a spring or springs that while the gradual compression of the spring or springs is occurring a gradually-increasing lever force, commensurate, or nearly so, therewith, comes into action to aid the governor of the engine in overcoming the same; second, in the arrangement in a governor of a nut-screw-rod, bevel-gear wheels, sliding rotary shaft, and pins, or their equivalents, for the purpose of regulating the quantity of steam with a slight movement of the balls and a small amount of power; third, in constructing the regulating screw-shaft in such a manner that crowding and breaking of the parts is obviated, and in so combining a spring, or its equivalent, with the screw-shaft and traveling nut thereof that the nut is kept in gearing position, notwithstanding that the shaft is constructed with a short screw-thread, which allows the nut to run fully out of gear before it strikes a fixed object.

To enable others skilled in the art to make and use my invention, I will proceed to describe its construction and operation.

A in Fig. 1 represents a standard of any suitable construction, on which the governor is mounted.

B is a vertical rod extending down loosely through the top support, a , of the standard, and finding its end support in the interme-

diate bearing, b , of the standard. This rod revolves, and has a short screw-thread, c , cut on its circumference midway of its length. Just below said screw-thread, and on a plain portion of the shaft, a spiral spring, d , is arranged, and on the screw portion of the rod a slide-nut, e , is fitted, so as to rise and fall between the legs of the standard. To this nut the connecting-rod f of the governor and valve movement is fastened.

C is a bevel-wheel attached to the upper end of the rod B, and revolves with it.

D is a horizontal tubular shaft arranged to revolve in bearings $g g$ of the standard. On this shaft two bevel-wheels, E E', are fitted loosely, so as each to alternately revolve with or independently of it, and to gear with the bevel-wheel C. In the inner face of each of the hubs of these wheels clutch-notches $h h' h'$ are formed. There is also a pulley, i , on one end of the shaft D for the belt of the main shaft to run upon.

F is a solid shaft, fitted loosely within the tubular shaft, so as to slide independently of it, but to revolve with it. From the circumference of this shaft, on opposite sides, and at points between the two bevel-wheels, pins $j j'$ project a short distance, oblong slots $k k$ being cut in the tubular shaft to allow for their protrusion through it, and also to admit of their moving along with the shaft, of which they form a part. The object of these pins is at certain periods to automatically gear the bevel-wheels with the vertical shaft B, and thereby, as the shaft revolves, produce a rotation of the bevel-wheel C and its rod B in a right or left direction, accordingly as the circumstances of the case may require. The pins enter the clutch-notches in the hubs of the bevel-wheels at the completion of the extent of the forward or back movement of the shaft F. If the pins $j j'$ enter the notches $h h'$, the screw-rod causes the slide-nut to gradually descend, and so operate upon the valve-movement as to cause it to gradually increase the size of the steam-escape passages; but if the pins $j j'$ enter the notches $h' h'$, the nut will be caused to rise, and the effect of the valve movement reversed. I would here state that if the shaft F is arranged to revolve in an opposite direction (by crossing the belt or otherwise) to that indicated by arrow in the drawings, the order

of the gearing of the bevel-wheels with it and the effect on the nut will be reversed, but still the end accomplished will be the same. I would also here state that in case the nut should from any cause descend so far as to get out of gear with the screw-thread *c*, the spring *d* acts always to force it up to a gearing position.

In order to effect the specified changes in the throw of the valve movement by means of the governor, I will in describing my improved governor show a method of doing the same.

G G are elbow-shaped arms of my governor. These arms are attached by means of pivots *l l* at their angle to a sliding collar, *o*, which attaches to the inclosed end of the solid sliding shaft *F* by means of pins *m m*, said pins protruding through oblong slots *n n* of the revolving tubular shaft, the slots *n n* being of a length corresponding to the necessary sliding movement of the shaft *F*. On the long ends of the elbow-arms the balls, vanes, or weights are attached, and to the short ends thereof links *H H* are pivoted, said links being also pivoted by their other ends to fixed ears or a collar, *I*, of the revolving but non-sliding tubular shaft *D*, as shown.

J is a spiral spring coiled round the tubular shaft between the sliding collar *o* and a stationary collar or shoulder, *p*, of the tubular shaft, as shown.

From the foregoing description it is evident that if the governor-balls gradually increase the extent of their outward movement from each other, the shaft *F* is caused to slide in the tubular shaft *D* and effect the necessary changes in the valve-gearing by reason of the approximation to a straight line of the short ends of the elbow-governor arms and the links, and that the spring at the same time is gradually compressed by the sliding collar *o*, and consequently is gradually offering a greater resistance to the spreading of the balls apart; and while this is the case the increased leverage brought to bear on the balls by the aforementioned gradual approach to a straight line of the arms and links compensates for the increasing rigidity of the spring.

In Figs. 4, 5, and 6 modifications of the manner of applying the spring *J* and of the means for effecting the alternate gearing of each of the bevel-wheels with the sliding shaft *F*, and of the mode of attaching the connecting-rod of the valve movement with the governor are shown. It will be seen that the spring *J* is arranged on the solid shaft *F*, and the collar *o* is made fast while the collar *I* is disconnected from the tubular shaft. It will further be seen that ratchet-teeth *j j' h h'*, instead of pins and notches, are provided for effecting the gearing of the bevel-wheels with the sliding shaft, and further that the slide-nut has two short journals, *s s*, projecting from its ends for a forked lever, *t*, to straddle, instead of a single pivot. I would here remark that the spring *J* might be placed between the two collars *I o*, as shown in red. In this

case it would be extended instead of compressed, as the arms and links assumed a straight line.

In Fig. 7 a modification of the lever arrangement, shown in Figs. 1, 2, and 3 is seen. It will be observed that the links *H* are pivoted to the sliding collar below the balls, instead of being pivoted to the stationary collar above the balls, and that they produce a gradually-increasing upward compression of the spring, and also at the same time act with a gradually-increasing thrust on the short ends of the elbow-arms *G*, and thus compensate for the increasing rigidity of the spring.

In Fig. 8 a modification of the arrangement of the collars and spring shown in Figs. 1, 2, and 3 is seen. It will be observed that the spring *J* is arranged outside of the collar *I*, and that the collar *I* is made to slide, while the collar *o* is made stationary.

In Fig. 9 a modification of the lever arrangement and spring is shown. Two additional links, *q q*, being interposed between the elbow-arms that carry the balls, and the sliding collar *o*, in such manner as to allow of the balls being located farther from the axis of the governor-shaft, and so as to compress the spring by a thrust upon it. The springs are also shown as coiled on separate rods arranged alongside the governor-shaft, and also made of corrugated metal and placed between the joints of the levers and the face of the fly-wheels.

In Fig. 10 a modification of the elbow-arms *G*, that carry the governor-balls and the sliding shaft *F*, is shown. It will be seen that a toothed wedge, *r*, is formed on the sliding shaft *F*, and that the short ends *z z* of the elbow-arms is in form of a scroll, and also provided with teeth. Further, that the spring is arranged between the tubular shaft *D* and the collar *I* on the end of the sliding shaft *F*. With this arrangement, when the balls fly out, the toothed scroll draws down the rod and causes a gradual compression of the spring, and while this is occurring the increased leverage afforded by the toothed wedge acts in concert with the decreasing leverage of the scroll ends of the arms that carry the balls to compensate for the gradually-increasing rigidity of the spring.

In Fig. 11 substantially the same principle as shown in Fig. 10 is seen applied in connection with the modification, Fig. 9.

In Fig. 12 a modification of the manner of employing the connecting-rod *f* of the valve movement is shown. It will be observed that the rod *f* is forked, as shown in Fig. 6, and connected directly to the throttle-valve of the engine.

In Fig. 13 is shown a modification of the rod *f*, whereby the rod itself answers for operating the throttle-valve. The change made consists in constructing the rod in two parts and fitting one part in a square socket, *u*, of the other, so that the rod may elongate or shorten as the screw-thread *c*, which in this

case fits a stationary nut, v , is operated upon by the said stationary nut. I would here state that the socket might be round and a screw-thread formed in its circumference for a screw-thread on the end of the upper portion of the rod to work in. In this case the stationary nut v , Fig. 13, would be unnecessary, and simply a plain square hole to admit the rod and prevent it turning substituted for it at the point where it is shown as located in said figure.

What I claim as my invention, and desire to secure by Letters Patent, is—

1. Arranging the arms or levers, constructed as described, of a governor, in relation to a spring or springs, in manner and for the purposes set forth.

2. The arrangement in a governor of the nut e , screw-shaft B, bevel-gear wheels C E E', sliding rotary shaft F, and pins or ratchets h h' , in the manner and for the purposes set forth.

3. So constructing the shaft B that the nut e is allowed a chance to run out of gear with the screw-thread of said shaft before a crowding and breaking of the parts of the machine occurs, and so combining a spring or its equivalent with the nut and shaft that the nut shall be kept in gearing position with the shaft, substantially as described.

LEWIS EIKENBERRY.
